CLAIM

The ornamental design for a CB charm, substantially as shown and described.

DESCRIPTION

FIG. 1 is an isometric view from an upper and forward aspect of a CB charm, showing my new design; FIG. 2 is a top plan view thereof;

FIG. 3 is a front elevational view thereof; FIG. 4 is a side elevational view from the left side thereof; and

FIG. 5 is a side elevational view from the right side thereof.

The rear of the charm is planar and of the same surface texture as the principal portions of the top and sides thereof.
